(57) **CLAIM**

The ornamental design for a vehicle wheel, as shown and described.

DESCRIPTION

FIG. 1 is a perspective view of a vehicle wheel according to our design;

FIG. 2 is a front view of the vehicle wheel; and,
FIG. 3 is a left side view of the vehicle wheel, with the right side view being, a mirror image. The top and bottom views are the same as the side views.

The broken line showing of an aperture for a valve stem is shown for environmental purposes only, and the shape and location of the aperture for a valve stem forms no part of the claimed design.
